UNITED STATES PATENT OFFICE

ROBERT T. POLLOCK, OF NEW YORK, N. Y., ASSIGNOR TO UNIVERSAL OIL PRODUCTS COMPANY, OF CHICAGO, ILLINOIS, A CORPORATION OF SOUTH DAKOTA

PROCESS FOR CONVERTING HYDROCARBON OILS

Continuation of application Serial No. 380,746, filed May 12, 1920. This application filed September 28, 1928. Serial No. 309,108.

This invention relates to improvements in a process and apparatus for converting hydrocarbon oils and refers more particularly to a process by which a greater quantity of the low boiling point hydrocarbons may be recovered in the initial cracking of the oil.

This application is a continuation of my application Serial No. 380,746, filed May 12, 1920.

Among the salient objects are to provide a process in which the raw oil, besides acting as a cooling agent to assist in condensing the higher boiling point cuts from the oil vapors, is at the same time, preheated by the vapors; to provide a process in which this condensation and preheating takes place without the oil vapors coming in contacting relation with the raw oil, thereby obviating the objectionable feature of having a substantial portion of the low boiling point vapors extracted with the higher boiling point fractions to combine with the reflux condensate; to provide a process in which the reflux may be combined with the raw oil subsequent to the dephlegmation of the vapors and one in which the relative proportions of the mixture may be positively controlled; to provide an improved apparatus for the carrying out of this process and in general to provide a process and apparatus of the character referred to.

The single figure in the drawing shows a diagrammatic elevational view of the apparatus.

Referring in detail to the drawing, the raw oil is charged from any convenient source to the pump 1 by the inlet pipe 2. From the pump it is directed through the line 3, which is controlled by a valve 4 to a coil 5 mounted within the partial condenser 6. This partial condenser comprises a casing member in which are circulated the oil vapors. The raw oil, after being preheated in this partial condenser is drawn off through the line 8, which is controlled by valves 9 and

10. A by-pass 11, controlled by a valve 12, furnishes a means for by-passing the raw oil around the partial condenser. The raw oil is supplied to a mixing tank 13, which is connected to the reflux collecting tank 14 by a fluid line 15, controlled by a valve 16 and a gas connecting line 17. The reflux collecting tank is supplied with reflux through the drawoff pipe 18, which is controlled by a valve 19. This reflux is taken from the bottom of the dephlegmator 20. By-pass lines 21 and 22 controlled by valves 23 and 24 respectively, furnish means of by-passing the reflux and the raw oil around the collecting tank 14 and mixing tank 13. When these tanks are cut out, the reflux combines with the raw oil directly. A secondary connecting line 25, controlled by valve 26, diverts the reflux from the drawoff line 18 to the tank 14. A similar line 27, controlled by valve 28 directs the raw oil with its reflux content to the charging line 29, controlled by a valve 30.

The oil charge is then supplied to the heating tubes 31, which are mounted above a furnace 32, the latter being preferably heated by gas burners 33. The heated oil, after being subjected to a cracking temperature, passes into the vapor chamber 34 through the connecting line 35. The oil vapors released in the vapor chambers are directed to the dephlegmator through the riser 36 and connecting line 37. A valve 38 is interposed in this line. The oil vapors which are introduced to the bottom of the dephlegmator rise through the successive stages in which they are dephlegmated by being caused to pass through shallow pools of reflux condensate, the level of which is maintained by suitable standpipes 40. After passing up through the successive stages through the risers 39, the uncondensed vapors pass off through the line 41 which is regulated by valve 42 and are circulated about the coil pipe 5, which is mounted in the partial condenser. The inter-

changing of heat which takes place in the partial condenser causes an additional portion of the higher boiling point hydrocarbons to condense from the vapors, and pass 5 back into the dephlegmator through the return line 43 regulated by valve 44. The uncondensed vapors from this partial condenser pass off through the gooseneck 45, which has interposed therein a valve 46. These vapors 10 are condensed in the spiral tube 47 which is mounted in a water condenser 48 and pass off as distillate through the drawoff line 49, controlled by valve 50 to a receiver in the tail house (not shown). A residuum drawoff 15 line 51 controlled by valve 52 is tapped into the vapor chamber for drawing off the heavier oils with the precipitated carbon.

The operation of the process is as follows: The raw oil is introduced to the partial condenser and preheated therein by having the 20 oil vapors circulated around a coil pipe through which the raw oil flows. After being preheated, the raw oil is directed to the collecting tank where it is combined with 25 regulated portions of reflux condensate supplied from the dephlegmator. The raw oil with its condensate content is then heated to a cracking temperature and the vapors released therefrom in the vapor chamber. 30 These vapors rise through the successive stages in the dephlegmator, the reflux being drawn off and supplied to the reflux collecting tank, from which it is added to the raw oil in regulated quantities or is supplied directly to the raw oil through the by-pass 35 lines. The uncondensed vapors on the other hand, rise through the dephlegmator and circulate about the coil containing the raw oil in the partial condenser where a portion of the 40 vapors are condensed and returned to combine with the reflux in the dephlegmator. The vapors not condensed pass over to be collected as distillate after being condensed in the water condenser. In this manner, it is 45 possible to preheat the raw oil and at the same time, take advantage of the cooling and condensing properties of the raw oil by circulating the vapors about a coil containing the incoming oil charge. At the same time, 50 this process obviates the objection of intermingling the raw oil and the vapors as this intermingling extracts a substantial portion of the lighter oil fractions from the vapors during dephlegmation. 55 The following is an illustrative run of the process: Charging gas oil from the mid-continent field of from 31° Baumé to 32° Baumé, and preheating the same in the partial condenser, then combining therewith the reflux 60 from the dephlegmator and heating the same to a temperature of approximately 800° F., in the heating tubes and a subsequent temperature of about 750° F., in the vapor zone, there is by weight from 5% to 20% vapors 65 released from the body of the oil which would

produce lighter fractions having an end point of approximately 450° F. After passing through the dephlegmator, 8% to 9% of said vapors are recovered as distillate in the receiver, while two or three per cent by weight 70 combine with the reflux and are returned to be retreated, after being mixed with the raw oil. By interchanging the heat of the vapors to the raw oil and taking advantage of the cooling and condensing properties of the 75 oil by contacting the vapors and the oil by radiation, the efficiency of the process is greatly increased, due to the fact that the incoming oil which has a very appreciable affinity for the lighter fractions of the oil, 80 is not permitted to contact the vapors in the manner that it may take these lighter fractions therefrom.

Having thus described my invention, what I claim is:

1. A continuous process for cracking hydrocarbon oil, consisting in raising the oil to a cracking temperature in a single pass through a heating zone, in delivering the heated oil to an enlarged reaction chamber, 90 wherein substantial conversion occurs, in subjecting the vapors to reflux condensation by causing them to initially pass through successive pools of reflux condensate free from other constituents, in then passing the 95 vapors in heat interchange relation with incoming charging oil, to preheat such incoming charging oil and separate from the vapors insufficiently cracked fractions, in subjecting the uncondensed vapors to final condensation, in uniting the preheated charging oil with regulated proportions of reflux condensate separated from the vapors in a mixing chamber, wherein a reserve supply of heated material for the process is maintained 100 and in continuously supplying the commingled reflux condensate and preheated charging oil from said mixing tank to said heating zone, and in maintaining a superatmospheric pressure on the oil undergoing conversion in the process.

2. A process for cracking hydrocarbon oil, consisting in raising the oil to a cracking temperature in a single pass through a heating zone, in delivering the heated oil to an 115 enlarged reaction chamber, wherein substantial conversion occurs and from which no unvaporized oil is permitted to return to said heating zone, in subjecting vapors evolved from the oil to reflux condensation by causing the same to initially pass through successive pools of reflux condensate free from other constituents, in thereafter causing the vapors to flow in heat interchange relation with incoming charging oil for the process, 120 to preheat such charging oil and condense insufficiently cracked fractions of the vapors, in uniting the insufficiently cracked fractions of the vapors condensed by passage in heat interchange relation with the charging 125 oil.

oil with the reflux condensate in the last pool through which the vapors pass, in subjecting the uncondensed vapors to final condensation, in uniting the preheated charging oil with predetermined proportions of reflux condensate in a mixing tank, wherein a heated supply of commingled charging oil and reflux condensate is maintained for the process, in continuously supplying such commingled oils from said tank to said heating zone, and in maintaining a superatmospheric pressure on the oil undergoing conversion in the process.

In testimony whereof I affix my signature.

ROBERT THOS. POLLOCK.
